UNITED STATES PATENT OFFICE.

LOUIS WOJIDKOW, OF BROOKLYN, NEW YORK.

DESIGN FOR A STAND FOR POTS OR KETTLES.

SPECIFICATION forming part of Design No. 27,938, dated December 7, 1897.

Application filed October 20, 1897. Serial No. 655,854. Term of patent 3½ years.

To all whom it may concern:

Be it known that I, LOUIS WOJIDKOW, a citizen of the United States, residing at Brooklyn, county of Kings, and State of New York, 5 have invented and produced a new and original Design for Stands for Pots or Kettles, of which the following is a specification, reference being had to the accompanying drawings, forming part thereof.

10 Figure 1 is a side elevation of a stand for pots and kettles showing my new design, and Fig. 2 is a plan view of the same.

The leading features of my design are a top ring formed with petaliform swells or bulges, 15 the ends of the petals extending above the top ring, so that a scalloped edge is formed thereon, and legs the upper ends of which are spread into fan shape and are longitudinally ribbed or corrugated.

20 A indicates the top ring, which is provided with petaliform swells or bulges *a*, having convex outer surfaces, the ends of the petal-shaped figures extending above the top ring, so that a scalloped edge *a'* is provided.

B indicates the legs, which are formed on 25 a compound curve and the upper ends of which are spread and gradually enlarged into fan shape and are provided on their outer surfaces with longitudinal ribs or corrugations *b*, which grow smaller gradually toward their 30 lower ends.

A petaliform and scalloped base-ring C connects the legs at their lower ends.

Having described my invention, what I claim as new, and desire to secure by Letters 35 Patent, is—

The design for a stand for pots and kettles and the like substantially as herein shown and described.

In testimony that I claim the foregoing as 40 my invention I have signed my name in presence of two subscribing witnesses.

LOUIS WOJIDKOW.
